ANTENNA SYSTEM

Frank O. Chesus, Jackson Heights, and Frank G. Thomas, Islip, N. Y., assignors to Federal Telephone and Radio Corporation, New York, N. Y., a corporation of Delaware

Application June 27, 1945, Serial No. 601,800

24 Claims. (Cl. 343—124)

1

The present invention relates to goniometers and particularly those adapted for use at very high frequencies.

Inductive goniometers have not been extensively used for very high frequencies primarily because either the coefficient of coupling between the rotor and stator was so low that there was a high insertion loss and/or where the insertion loss was small, the stator field distribution was non-uniform and therefore contributed to goniometer error.

An object of the present invention is the provision of an improved inductive goniometer, particularly adapted for operation at very high frequencies.

Another object of the present invention is the provision of a goniometer of relatively high accuracy, and particularly adapted for operation at very high frequencies.

Another object of the present invention is the provision of a goniometer in which the rotor and stator are relatively closely coupled and which provides for accurate operation over a relatively wide band.

Another object of the present invention is the provision of a goniometer which provides within itself for impedance transformation, thus eliminating the necessity for impedance transformers between the antennas and the direction finding receiver.

Still another object of the present invention is the provision of an improved direction finder employing goniometers embodying our invention.

Other and further objects of our invention will become apparent and the invention will be best understood from the following description thereof, reference being had to the drawings, in which:

Fig. 1 is a schematic diagram of a goniometer embodying our invention, showing the connection of the goniometer to a direction finder antenna system;

Fig. 2 is a perspective view of a goniometer of the type schematically illustrated in Fig. 1, further showing, in block diagram, its relation to the rest of a direction finder;

Fig. 3 is a schematic diagram of a modified form of goniometer finder providing for impedance transformation embodying our invention;

Fig. 4 is a plan view, partly in outline, of a portion of a goniometer of the type illustrated schematically in Fig. 3 embodying our invention; and

Fig. 5 is a side elevational view of part of another type goniometer embodying our invention.

2

Referring now to Fig. 1, the goniometer there illustrated, generally designated by the numeral 1 is comprised of two coaxial annular members or rings 2 and 3 of conductive material, the outer ring 2 being the stator and the inner ring 3 being the rotor. The rings 2 and 3 are each in the form of a completely closed single loop. The stator 2 and the rotor 3 lie in the same or substantially the same plane adjacent each other with the rotor 3 adapted to rotate in said plane about a central axis 4 which is perpendicular to said plane. A pair of leads 5 and 6 are connected to substantially diametrically opposite points on said rotor at one of their ends and the other ends are adapted to be coupled to the direction finding receiver.

The antenna system is connected to substantially symmetrically and equally spaced points on the stator 2 with each of the individual antenna units coupled to one of said points. For example, in an Adcock array of the type having four spaced antenna units 7-10 arranged to produce a crossed figure-of-eight reception pattern with antenna units 7 and 9 forming one of said pairs and antenna units 8 and 10 forming the other pair which is crossed at right angles to the first pair, all of said units being substantially equidistant from a central point, antenna units 7 and 9 are connected to diametrically opposite points on the stator 2 while antenna units 8 and 10 are likewise connected to diametrically opposite points on said stator 2, but the latter opposite points are at 90° to said first-mentioned points. Of course, it is to be understood that the antenna arrangement here described is only by way of example and that numerous other types of antenna arrangements, such as for example, crossed loops or crossed dipoles as well as other antenna systems not producing a figure-of-eight, may likewise be connected to equally and/or symmetrically spaced points on the stator. Furthermore, three symmetrically disposed antenna units may be connected to the stator at three symmetrical points on the stator, or four antenna units may be connected to symmetrical but not equally spaced points on said stator.

Assuming a wave to be approaching the antenna system in such a direction that at a given instant, current tends to flow from antenna 8 and into antenna 10, the current will divide itself in the stator 2 as indicated by the arrows. This will induce a current flow in the rotor 3 such that when the rotor is in the position indicated in Fig. 1, current will tend to flow in through lead 6 toward the rotor and out through lead 5,

55

and in this position a maximum transfer of energy would occur between the stator 2 and rotor 3. However, if the rotator rotates so that the leads 5 and 6 are in the position indicated by the broken lines 11 and 12, the minimum transfer energy will occur between the stator and rotor. In the foregoing analysis, no reference has been made to the current flowing from antennas 7 and 8. In the conventional antenna system or in the antenna system of the type hereinabove described, when a wave is approaching so as to induce a current flow from antenna 8 to antenna 10, either no voltage will be induced in antennas 7 and 8 or the voltages that are induced will be the same so that when these antennas 7 and 8 are connected to the stator 2, they tend to drive current in opposite directions through the stator and thereby neutralize each other's effect.

Referring now to Fig. 2, a physical embodiment of the type of goniometer shown schematically in Fig. 1 is there illustrated. The stator 2 is in the form of a trough within which the rotor 3 rotates thereby producing extremely closely coupling approaching unit coupling. The rotor 3 is mounted on a disc 13 of insulating material which is carried on a rotatable shaft 14, said shaft being hollow so that the leads 5 and 6 may be brought into said shaft and carried therein. Shaft 14 is driven by a motor 15 which may be also employed to control the generation of the sweep of an oscilloscope 16 at the output of a direction finding receiver 17 so as to synchronize the sweep with the rotation of rotor 3. To provide for coupling of leads 5 and 6 to the direction finding receiver 17, a coupling transformer 18 is provided having a rotating conductive member 19 in the form of a conductor split at 20, the leads 5 and 6 being carried through shaft 14 and connected to the free ends of the rotor member 19 at said split 20, the rotor member 19 being mounted on a disc 21 which is also carried on shaft 14 whereby the rotor member 19 rotates at the same rate as the rotor 3. Rotator member 19 rotates within the trough of a coaxial circular conductive stator member 22 similar to stator 2 except that stator member 22 is also split and the ends of said stator members 23 and 24 at said split are connected by leads 25 and 26, respectively, to the direction finding receiver 17.

Assuming that instantaneous current conditions prevail in the goniometer of Fig. 2 such as are indicated by the arrows in Fig. 1, current tends to flow through leads 5 and 6 in the direction indicated by the arrows, the current also flowing through rotor 19. The current flowing through rotor 19 induces opposite currents on the inner surface of the stator 22, these currents then causing current to flow through leads 25 and 26 as indicated by the arrows. Thus, the coupling transformer 18 serves to couple the rotating leads 5 and 6 to the stationary leads 25 and 26 and thence to the direction finding receiver.

Under certain circumstances the inductance of a single closed loop stator or rotor may be insufficient, particularly at the lower wavelengths or when an impedance transformation is desired between the antennas and the direction finding receiver. Under such circumstances, the loop may be doubled back on itself, care being taken that the current in the loop flows in the same direction through the doubled portions. For example, referring to Fig. 3, a goniometer 27 is there illustrated providing for impedance transformation in which the stator 2 is in the form of

6 a single loop while the rotor 28 is in the form of a double loop. The rotor 28 consists of four semi-circular strands of wire 29-32, strands 29 and 30 being on one side of the line defined by a diameter between leads 5 and 6 and strands 31 and 32 being on the other side. It will be seen that in order to have the current induced in strands 29 and 30 flowing in the same direction, these two strands must have their opposite ends connected together as, for example, by lead 33 while the same function is performed for strands 31 and 32 by lead 34. Leads 33 and 34 by reason of their location do not materially interfere with the operation of the goniometer. The current flow is indicated by the arrows in said figure.

While in Fig. 3 the rotor is shown as being doubled, it is also apparent that the same construction may be used to provide a doubled stator 20 which is particularly desirable as the wavelengths are increased to provide the additional inductance needed for proper impedance matching. Furthermore, while the doubled rotor or stator 25 may be in the form illustrated in Fig. 3, other convenient forms may be used in place thereof. For example, in Fig. 4 the doubled rotor 35 consists of two semi-circular coaxial lines 36 and 37 arranged in the form of a circle, lead 6 being connected to one end of the inner conductor 38 of coaxial line 37 at one point of said circle, with the inner conductor 39 of line 36 connected to the outer conductor 40 of line 37 at the same point of said circle. At a diametrically opposite point of said circle, lead 5 is connected to the free end of inner conductor 39 while the free end of inner conductor 38 is connected to the outer conductor 41 of line 36. Also, outer conductors 40 and 41 are interconnected at their free ends by conductor 42 located along a diameter of the circle. It will be seen that the induced current flow in the rotor 36 is in a series circuit as indicated by the arrows. Viewed, however, from the circle as constituted by the two outer conductors 40 and 41, the paths of induced currents therein are generally speaking parallel over the two semi-circles, so that the effect of a doubled loop is produced, thus increasing the inductance of the rotor 35. A similar construction may be used for the stator.

50 While in Figs. 1-3, we have illustrated the rotor as arranged within the stator, it will be apparent that the rotor may be arranged adjacent the stator in a plane parallel to the stator or, if desired, two stators 42 and 43 may be used, each coupled to a separate pair of antenna units, as is illustrated, for example, in Fig. 5, in which antennas 8 and 10 are connected to one stator and antennas 7 and 9 are connected to the other stators in a position at right angles to the connections of the first stator. In some cases the stators may be similar in construction to that shown in Fig. 4. The rotor 44 is positioned between the two stators in planes parallel to said stators and may be rotated by shaft 14 with the various leads passing through said shaft to a coupling transformer of the type designated by numeral 18 in Fig. 2.

70 While we have described various specific embodiments of our invention, it will be apparent to those versed in the art that numerous modifications may be made in the structures without departing from the teachings of our invention. For example, the rotor 3 in Fig. 1, need not rotate as a unit but the leads 5 and 6 may be rotated about a fixed ring to produce the same effect as if the

entire rotor 3 were rotated. Likewise it will be apparent that the rotor and stator may be changed in position, and the rotor may be in the form of a trough. Furthermore, while we have described the antenna units as "connected" at various points to the stator and the leads 5 and 6 "connected" to the rotor, it will be apparent that these connections could be replaced by couplings other than galvanic. Furthermore while, for the sake of clarity, the leads 5 and 6 have been shown as single conductors, it will be apparent to those versed in the art that in actual practice these conductors may be in the form of coaxial lines. Various other modifications will readily occur to those versed in the art. Accordingly, while we have described above the principles of our invention in connection with specific apparatus, and particular modifications thereof, it is to be clearly understood that this description is made only by way of example and not as a limitation on the scope of our invention as defined in the accompanying claims.

We claim:

1. A goniometer comprising a pair of conductive members inductively related by a substantially uniform field, one of said members having coupling means connected to substantially symmetrically spaced points thereon, a pair of leads coupled to symmetrical points on the other conductor, and means for effectively rotating the position of said points of said coupling to said other member relative to said one member.

2. A goniometer for coupling to an antenna system comprising a pair of coaxial annular conductive members positioned adjacent each other, one of said members adapted to be separately connected to said antenna system at substantially symmetrically spaced points thereon, a pair of leads coupled to substantially diametrically opposite points on the other member, and means for effectively rotating the position of said coupling to said other member relative to said one member.

3. A goniometer comprising a pair of coaxial annular conductive members positioned adjacent each other, a plurality of input leads connected to one of said members at equally spaced points thereon, a pair of output leads connected to substantially diametrically opposite points on the other member, and means for effectively rotating the position of the points of connection of said output leads relative to said one member.

4. A goniometer according to claim 1 wherein said members are substantially similar in shape.

5. A goniometer according to claim 1 wherein said members lie in the same plane.

6. A goniometer according to claim 1 wherein said members lie in parallel planes.

7. A goniometer according to claim 1 wherein each of said members is in the form of a completely closed single loop.

8. A goniometer according to claim 2 wherein each of said members is in the form of a completely closed single loop.

9. A goniometer according to claim 1 wherein one of said members is in the form of a trough with the other member arranged within said trough.

10. A goniometer for an antenna system comprising a pair of coaxial annular conductive members positioned adjacent each other, one member being adapted to be separately coupled to the antenna system at substantially symmetrically spaced points on said one member, a pair of leads coupled to substantially diametrically opposite

points on the other member, and means for producing effective relative rotation between said members.

5 11. A goniometer for an antenna comprising a coaxial annular conductive stator and annular conductive rotor positioned adjacent each other, said stator being adapted to be separately coupled to the antenna system at substantially symmetrically spaced points on said stator, a pair of leads coupled to substantially diametrically opposite points on said rotor, and means for rotating said rotor.

10 12. A goniometer according to claim 11 wherein said members lie within the same plane, one of said members being inside the other.

15 13. A goniometer according to claim 11 wherein said members lie in parallel planes.

20 14. A goniometer according to claim 11 wherein one of said members is in the form of a trough with the other member arranged within said trough.

25 15. A goniometer according to claim 11 wherein said members are each in the form of a completely closed single loop.

16. A goniometer according to claim 11 wherein said stator is in the form of a trough with the rotor rotating within said trough.

30 17. A goniometer according to claim 11 and further including stationary lead and means for coupling said pair of leads to said stationary leads.

18. A goniometer according to claim 11 further including a pair of stationary leads and means for coupling said leads to said stationary leads, 35 said means comprising a pair of coaxial split rings arranged immediately adjacent each other, one of said rings being rotatable, said leads being connected to the free ends thereof at said split, and a pair of stationary leads connected to the free ends of the other ring at its split, the rotatable ring being adapted to rotate synchronously with said rotor.

19. A goniometer according to claim 1 wherein 45 said other member comprises a pair of semi-circular coaxial lines arranged in the form of a circle with the inner conductor of one line connected to the outer conductor of the other at one point of said circle, and at the diametrically opposite point of said circle the outer conductor of said one line is connected to the inner conductor of said other line, with said leads being connected to the free ends of the inner conductors of each line.

20. A goniometer for an antenna system comprising a pair of conductive members inductively related by a substantially uniform field, one of 55 said members having means for coupling said antenna system to substantially symmetrically spaced points thereon, a pair of leads connected at symmetrical points on the other conductor, thereby effecting connection between said leads over generally parallel paths in said other member, means for effectively rotating the position of said coupling to said other member relative to said one member, and means for effecting impedance transformation between said members comprising additional series circuit connections to the conductors of said one member, whereby induced currents make repeated traversals of said paths.

21. A goniometer according to claim 20, wherein the rotating means serves to rotate said other member, and the impedance transformation means is applied to the rotated member.

70 22. A goniometer according to claim 20, where-

in the means for effecting impedance transformation includes return loops in said paths.

23. A goniometer according to claim 20, wherein the means for effecting impedance transformation includes coaxial lines in said paths.

24. A direction finder collector system comprising two crossed pairs of spaced antenna units symmetrically disposed about a central axis, and a goniometer comprising three coaxial annular conductive members positioned adjacent each other and lying in parallel planes, means coupling the antenna units of one pair to diametrically opposite points on the upper of said members,

means coupling the antenna units of the other pair to diametrically opposite points on the lower member which points are at right angles to said first mentioned points, a pair of leads coupled to substantially diametrically opposite points on the middle member, and means for effectively rotating the position of the points of connection of said leads relative to said upper and lower members.
